MERCURY BOILER

Howard J. Kerr, Westfield, N. J., assignor to The Babcock & Wilcox Company, Bayonne, N. J., a corporation of New Jersey

Application September 25, 1928, Serial No. 308,320
Renewed January 3, 1933

8 Claims. (Cl. 122—312)

This invention relates to a mercury boiler that comprises a plurality of long narrow drums or headers each having mercury vapor generating tubes depending therefrom and communicating with the interior of the headers. The invention will be understood from the description in connection with the accompanying drawings in which Fig. 1 is a vertical section through an illustrative embodiment of the invention; Fig. 2 is a somewhat diagrammatic section along the line 2—2 of Fig. 1; Fig. 3 is a section on an enlarged scale showing some of the details, taken along the line 3—3 of Fig. 4; Fig. 4 is a longitudinal section through one of the drums, partly broken away; Fig. 5 is a plan view of the drum from below, partly broken away; and Figs. 6 to 11 are sections through drums showing modifications.

In the drawings, reference character 1 indicates a furnace that may be fired in any convenient way, and is provided with a rear upward extension 2 where the mercury boiler is located. The mercury boiler comprises a plurality of horizontally disposed headers 3 that are parallel to each other. The hot gases pass out through the outlet or stack 2' or may pass out through the spaces between the headers. The headers 3 may be made rectangular, circular in cross section or other suitable shape to resist internal pressure and receive the tubes. The headers may be hung from supports 4 by means of suspension members 5 that are attached to the headers 3 in any convenient manner, such as welding, for example.

Mercury may be introduced into the headers through the inlets 6. The liquid spaces of all headers are connected together by connections 6 and 7 and the vapor spaces by connections 8, to which a level indicator (not shown) is attached. Mercury vapor outlets 9 are provided in the upper portions of the drums and may be connected to a header 9'.

Rows of depending and preferably slightly divergent tubes 12 are connected to each one of the headers 3 and are located in the extension 2 so that the hot gases from the furnace 1 sweep across them. The lower ends of the tubes 12 are closed and the upper ends may be screwed into threaded holes in the lower portions of the headers 3, or the tubes may be connected into the headers in any other convenient manner that insures tightness. An extension 14 projects from the upper end of each tube 12 into the drum, and is provided with an upper reduced diameter or neck portion. Each tube is provided with a displacer having a longitudinal hole and having between the tube and the displacer, a narrow annular passage in which

the mercury is vaporized, the center hole supplying mercury at the bottom of the tube to the annular boiling chamber to replace that which is evaporated and that liquid which is expelled at the top by the rapid upward flow of the vapor. As shown the displacer is hollow and is made of an outer tube 18 and an inner tube 19, the space between them being closed at both ends. At the top end the closure is made by a shaped plug 15 projecting up into the bottle neck of the tube and beyond it with a deflector 17 on the top. An annular space is left between the plug 15 and extension 14 which communicates with the corresponding passage between the tube 12 and displacer-tube 18. The plug 15 has a central hole and nipple 21 connects its central hole with the bottom of the header space outside of the top end of the tube. At the bottom end the displacer is closed by bringing the inner tubes 19 and the outer tubes 18 together. Projections 22 on the displacer keep it at a proper distance from the tube at sides and bottom.

The tubes are located in the bottom of each header so that a shallow pool of liquid in the bottom of the header may flow freely into each of the holes 21 and through the displacer hole supplying the boiling annulus of each tube at its closed bottom end. The rapidly rising stream of mixed vapor and liquid next to the tube wall is deflected inward and upward between the contracted bottle neck extension of the tube top 14, and the stem of the displacer top 16, and so strikes the deflector 17 in the form of an annular stream of small diameter and high velocity. This deflector is preferably curved on its underside so as to change the direction of the stream reversing it so it leaves with a downward and outward direction. The effect of this is to separate liquid from vapor, the liquid being deposited in the bottom of the header to keep the pool supplied along with new feed supply, and the vapor rises to the outlet after passing a baffle 23 which serves as a secondary main or general separator.

By this construction each tube is provided with its own separator at the top of the rising leg of its circulating system, and each tube makes vapor and separates it from liquid independent of all other tubes, the header merely acting as a common vapor collector, and a common liquid reservoir to supply the tubes. The construction permits operation with least volume of mercury, and makes tube replacement easy in case of accidental damage as no internal connection to drum parts is required. The multiplicity of headers for

- a given number of tubes gives good heat transfer conditions because the gas stream is much sub-divided as it passes upward over tubes and between headers. The fact that tubes are not connected to any internal parts of the drum such as drum displacers used in other forms of mercury boilers, makes it unnecessary to provide the drums or headers with removable heads and so avoids the difficulties of strong tight joints for such heads. The ends of the headers are permanently closed, preferably by welding and in Figs. 3, 4 and 5, round discs are used to close the rectangular section headers after the ends are forged out to circular section.
- In the modification shown in Fig. 6, the header 3 is shown as being circular in cross section and inserts or fillers 25 are provided in the lower portion of the drum. The inserts 25 have flat upper surfaces that terminate near the upper ends of the nipples 21 so that it is not necessary to maintain a large body of mercury in the drum in order for the same to enter the tubes 12. Tubes merely pass through these fillers, the presence of which does not affect the attachment or removal of a tube.
- In the modification shown in Fig. 7, the drum 3 is cylindrical except for flat portions 27 into which the rows of tubes 12 are screwed, so as to enter the drum approximately radially.
- In the modification shown in Fig. 8, the header 3 is circular in cross section, the tubes 12 enter approximately radially and the tubes are staggered in two rows that are closely spaced.
- In the modification shown in Fig. 9, three rows of tubes are shown entering the header 3, which is of circular section with the lower portion flattened where the tubes enter as indicated at 28.
- In the modification shown in Fig. 10, the header 3 is circular in section and the lower portion is provided with inserts or fillers 30 to decrease the amount of mercury required. The tubes are welded to the header at the circumference of rings attached to the tubes as indicated at 31.
- In the modification shown in Fig. 11, provision is made for installing three rows of tubes parallel to each other, and entering the circular section header radially. The screw threaded holes in the lower portion of the header 3 are provided with threaded nipples 33, to which the tubes 12 are connected by means of the union nuts 34, the upper flaring ends of the tubes 12 being pressed against the outer ends of the nipples 33 as indicated at 35. The tubes in the central row 12 are straight and the tubes in the outer rows are bent at their upper ends as indicated at 12', so as to make the tubes parallel with each other though they may diverge.
- By this invention each tube can be completely manufactured separate from the drums and the only assembly that is necessary is the attachment of the tubes to the drums. Also when filler blocks are used in the drums, it is not necessary to have any connection between the tubes and the blocks.
- I claim:
1. In a mercury boiler, a tube with one end closed and the other end constricted, said tube containing a mercury displacer having a central longitudinal hole, said displacer nearly filling said tube but leaving a narrow annular passageway for rising mercury vapors, and a deflector above the upper end of said tube.
  2. In a mercury boiler, a tube with one end closed and the other end reduced in diameter and a mercury displacer in said tube of larger diameter than the inside diameter of said reduced end and of smaller diameter than the inside diameter of the main portion of said tube.
  3. In a mercury boiler, a header, a plurality of depending tubes extending into the lower portion of said header, each of said tubes containing a mercury displacer having a central longitudinal hole, said displacer nearly filling said tube but leaving a narrow annular passageway for rising mercury vapors, and an extension projecting into said header and constricting the tube discharge to a small annular hollow stream, and spray deflectors above the upper ends of said tubes.
  4. In a mercury boiler, a header, a plurality of depending tubes extending into the lower portion of said header, each of said tubes containing a mercury displacer having a central longitudinal hole, said displacer nearly filling said tube but leaving a narrow annular passageway for rising mercury vapors, said tube and displacer each provided with similarly shaped and spaced extensions forming a vapor outlet discharging a hollow annular stream, and connections between said central longitudinal hole and the inside of the header below the upper ends of said extensions.
  5. In a mercury boiler, a header, a plurality of depending tubes extending into the lower portion of said header, each of said tubes containing a mercury displacer having a central longitudinal hole, said displacer nearly filling said tube but leaving a narrow annular passageway for rising mercury vapors, and an extension for said tube and for said displacer and projecting into said header and cooperatively shaped to restrict the tube outlet to the discharge of a hollow annular stream, the upper end of said passageway extending above said displacer.
  6. In a mercury boiler, a header, a plurality of depending tubes extending into the lower portion of said header, each of said tubes containing a mercury displacer having a central longitudinal hole, said displacer nearly filling said tube but leaving a narrow annular passageway for rising mercury vapors, and extensions on the tube and displacer projecting into said header and cooperatively shaped and spaced to discharge a hollow annular stream, and connections between said displacer holes and the inside of said header, the upper ends of said connections terminating at approximately the same level.
  7. In a mercury boiler, a horizontal header, closed end tubes each containing a displacer dividing the tube space into liquid and vapor passageways, and each having a vapor and liquid separator at the open end thereof, said header having tube receiving openings constructed to pass therethrough the aforesaid separators, and means securing the tubes in position with respect to the said header.
  8. In a boiler, a horizontal header having tube receiving openings, tubes entering said header through the openings and arranged to carry liquid and vapor to said header, a separator at the header end of each tube, said tube receiving openings being constructed to pass the aforesaid separators therethrough, and means securing the tubes in position with respect to said header.

HOWARD J. KERR.
